(57) **CLAIM**

The ornamental design of the helmet, as shown and described.

DESCRIPTION

FIG. 1 is a front isometric view of a first embodiment of a helmet;

FIG. 2 is a side view of the helmet of FIG. 1;

FIG. 3 is a rear isometric view of the helmet of FIG. 1;

FIG. 4 is a front elevation view of the helmet of FIG. 1;

FIG. 5 a rear elevation view of the helmet of FIG. 1;

FIG. 6 is a top plan view of the helmet of FIG. 1;

FIG. 7 is another front isometric view of the helmet of FIG. 1;

FIG. 8 is another side view of the helmet of FIG. 1;

FIG. 9 is a rear isometric view of the helmet of FIG. 1;

FIG. 10 is a front isometric view of a second embodiment of a helmet;

FIG. 11 is a side view of the helmet of FIG. 10;

FIG. 12 is a rear isometric view of the helmet of FIG. 10;

FIG. 13 is a front elevation view of the helmet of FIG. 10;

FIG. 14 is a rear elevation view of the helmet of FIG. 10;

FIG. 15 is a top plan view of the helmet of FIG. 10;

FIG. 16 is another front isometric view of the helmet of FIG. 10;

FIG. 17 is another side view of the helmet of FIG. 10; and,

FIG. 18 is a rear isometric view of the helmet of FIG. 10.

The details shown in broken lines form no part of the claimed design.

1 Claim, 18 Drawing Sheets
